UNITED STATES PATENT OFFICE.

ROBERT FULLERTON, OF DES MOINES, IOWA.

PNEUMATIC LOG-SAW.

No. 853,350.

Specification of Letters Patent.

Patented May 14, 1907.

Application filed January 10, 1905. Serial No. 240,396.

To all whom it may concern:

Be it known that I, ROBERT FULLERTON, a citizen of the United States, residing in Des Moines, county of Polk, and State of Iowa, 5 have invented a new and useful Improvement in Pneumatic Log-Saws, of which the following is a specification.

The object of my invention is to provide a mechanical means for sawing down trees in a 10 forest, which may be easily and quickly manipulated and operated by two men and which will work with such rapidity that the largest and toughest trees may be felled in an exceedingly short length of time.

15 A further object is to construct such a means in such a light and compact manner as to make it portable by the operators and to be adapted for use in sawing logs as well as in cutting timber.

20 A further object is to provide such a means in a simple, strong, durable and inexpensive construction.

25 My invention consists of certain details of construction hereinafter set forth pointed out in my claims and illustrated in the accompanying drawings in which

Figure I shows a side elevation of my device, the chain belt saw being removed and the central portion being broken away; Fig. 30 II shows a transverse section of the chain belt saw; Fig. III shows a transverse section of the framework I employ; Fig. IV shows a plan view of my device the chain belt saw being removed and a part of the central portion 35 being broken away; Fig. V shows a longitudinal sectional view one of the plates I employ being removed; Figs. VI, VII, VIII, IX, X, & XI show detail views of my device. The Fig. XII shows a plan view of a portion of 40 my device, the chain belt saw being shown in position on the track.

45 Referring to the accompanying drawings the reference numeral 10 is used to indicate one of the side plates I employ in the construction of the framework on which my improved saw is designed to operate and the numeral 11 indicates the other plate or companion plate the two said plates being exactly 50 similar in every respect and each being provided with concave ends for purposes hereinafter stated. Riveted between said plates and extending above their upper edge surfaces for their entire lengths is a metal bar 12 said bar being provided with a centrally located longitudinal ridge or raised portion 13 said raised portion having vertical sides and

extending along the entire length of the bar 12 and designed to be employed as a track for purposes hereinafter stated. The numeral 14 indicates a like metal bar riveted between 60 the said plates 10 and 11 at their under edge surfaces said bar being provided on its outer longitudinal surface with a centrally located ridge or raised portion 15 exactly similar to the raised portion 13 and designed to be operated as a companion track therewith.

Secured in an adjustable manner to one of the ends of the frame work described is a support frame 16 within which a gear or sprocket wheel 17 is designed to be mounted 70 on a shaft 18 having its bearings in the sides of the said frames the said gear wheel being designed to be located therein in such a manner as to be in line with the tracks 13 and 15 and to operate within the concaved end of 75 the frame-work described. The shaft 18 on which the gear wheel 17 is mounted is designed to be operated by a small engine or compressed air machine 19 affixed on the outside of the frame work.

80 The numeral 20 indicates a handle secured to the support frame 16. The numeral 21 indicates a support frame, secured to the other end of the frame before described, said support frame being similar in every respect 85 to the support frame 16 and adapted to support a gear or sprocket wheel 22 designed to operate within the concaved end of the frame work and to be employed as an idler over which the chain belt as hereinafter described 90 operates.

The numeral 22^a indicates a handle secured to the support frame. The saw portion proper of my device, comprises a chain designed to travel on the tracks 13 and 15, composed of a triple series of links 23—24—25 respectively. The links 23 are constructed with a tooth 26 on the forward portion of its upper surface and having its under surface curved downwardly at 27 and the links 24 100 are constructed with a downwardly curved under surface, 28 exactly similar to the under surface of the link 23 and having a tooth 29 on the rear portion of its upper surface. The link 25 is constructed with a tooth 30 located centrally on its upper portion, all of 105 said links being provided with two transversed channels designed to receive rivets when the links are combined into a chain.

In combining the links to form the chain 110 belt saw, all of the links 23 are arranged on one side thereof and all of the links 24 are ar-

ranged on the other side thereof, the links 25 being designed to be placed between the links 23 and 24 and the links thus arranged are riveted together. By this combination all of 5 the teeth on one side of the chain belt saw are on the forward part of the links and all of the teeth on the other side are on the rear part of the links and the teeth on the links between the links just described assume a 10 position between the two. The rivet holes in the various links described are arranged in such a manner as to provide for the downwardly projecting curved portion 27 and 28 on the links 23 and 24 extending below the 15 under surface of the links 25. The width of the link 25 is by construction equal to the width of the tracks 13 and 15, and the face of the tooth on this link is at right angles to the sides thereof. The chain belt saw being thus 20 formed is placed on the tracks 13 and 15 and over the gear or sprocket wheels 17 and 22, and adjusted and the mechanism of my device is then complete.

In practical operation the power being applied through the compressed air machine or engine 19 the cutting chain belt is started in 25 operation on the tracks 13 and 15 by means of the drive wheel 17 and the operators conveying said device by the handles 20 and 22 30 approach a tree or log to be sawed and hold the rapidly moving chain against the same. As the chain revolves the teeth 26 and 29 cut the kerf and the teeth 30 on the centrally located links 25 clean the kerf.

Having thus described my invention, what 35 I claim and desire to secure by Letters Patent of the United States is;

1. In a pneumatic saw the combination of a triple set of links designed to be operated, by means of sprocket wheels, over a track 4 constructed on a frame work, the links on one side of the chain being provided with teeth on the forward portions of their upper surfaces and the links on the other side being provided with teeth on the rear portion of 45 their upper surfaces, all of said links being curved downwardly on their upper surfaces; a series of links provided with teeth on their upper surfaces mounted between the links on each side of the chain substantially as and 50 for the purposes stated.

2. In a pneumatic saw a combination of a frame work composed of two lateral plates 10 and 11 secured to tracks 13 and 15; a support frame 16 having a gear wheel 17 driven by an engine 19 mounted thereon, secured in an adjustable manner to one end of the frame work, a handle 20 secured to said support frame 16; a second support frame 21 in which is mounted a gear wheel 22 secured in an adjustable manner to the other end of the frame work, a handle secured to said support frame 21; a chain composed of links 23 and 24 provided with teeth 26 and 29 respectively on their upper surfaces, their under surfaces being projected downwardly; links 25 provided with teeth 30 on their upper surfaces arranged between the links 23 and 24, all arranged and combined substantially as and 60 for the purposes stated.

ROBERT FULLERTON.

Correction in Letters Patent No. 853,350.

It is hereby certified that in Letters Patent No. 853,350, granted May 14, 1907, upon the application of Robert Fullerton, of Des Moines, Iowa, for an improvement in "Pneumatic Log-Saws," an error appears in the printed specification requiring correction, as follows: In line 47, page 2, the word "upper" should read *under*; and that the said Letters Patent should be read with this correction therein that the same may conform to the record of the case in the Patent Office.

Signed and sealed this 4th day of June, A. D., 1907.

ranged on the other side thereof, the links 25 being designed to be placed between the links 23 and 24 and the links thus arranged are riveted together. By this combination all of 5 the teeth on one side of the chain belt saw are on the forward part of the links and all of the teeth on the other side are on the rear part of the links and the teeth on the links between the links just described assume a 10 position between the two. The rivet holes in the various links described are arranged in such a manner as to provide for the downwardly projecting curved portion 27 and 28 on the links 23 and 24 extending below the 15 under surface of the links 25. The width of the link 25 is by construction equal to the width of the tracks 13 and 15, and the face of the tooth on this link is at right angles to the sides thereof. The chain belt saw being thus 20 formed is placed on the tracks 13 and 15 and over the gear or sprocket wheels 17 and 22, and adjusted and the mechanism of my device is then complete.

In practical operation the power being applied through the compressed air machine or engine 19 the cutting chain belt is started in 25 operation on the tracks 13 and 15 by means of the drive wheel 17 and the operators conveying said device by the handles 20 and 22 30 approach a tree or log to be sawed and hold the rapidly moving chain against the same. As the chain revolves the teeth 26 and 29 cut the kerf and the teeth 30 on the centrally located links 25 clean the kerf.

Having thus described my invention, what 35 I claim and desire to secure by Letters Patent of the United States is;

1. In a pneumatic saw the combination of a triple set of links designed to be operated, by means of sprocket wheels, over a track 4 constructed on a frame work, the links on one side of the chain being provided with teeth on the forward portions of their upper surfaces and the links on the other side being provided with teeth on the rear portion of 45 their upper surfaces, all of said links being curved downwardly on their upper surfaces; a series of links provided with teeth on their upper surfaces mounted between the links on each side of the chain substantially as and 50 for the purposes stated.

2. In a pneumatic saw a combination of a frame work composed of two lateral plates 10 and 11 secured to tracks 13 and 15; a support frame 16 having a gear wheel 17 driven by an engine 19 mounted thereon, secured in an adjustable manner to one end of the frame work, a handle 20 secured to said support frame 16; a second support frame 21 in which is mounted a gear wheel 22 secured in an adjustable manner to the other end of the frame work, a handle secured to said support frame 21; a chain composed of links 23 and 24 provided with teeth 26 and 29 respectively on their upper surfaces, their under surfaces being projected downwardly; links 25 provided with teeth 30 on their upper surfaces arranged between the links 23 and 24, all arranged and combined substantially as and 60 for the purposes stated.
